Attorneys.

UNITED STATES PATENT OFFICE.

FREEMAN CASS, OF BROOKLYN, NEW YORK.

FEED-ROLLER FOR SPINNING MECHANISM.

1,367,300.

Specification of Letters Patent. Patented Feb. 1, 1921.

Application filed April 13, 1920. Serial No. 373,516.

To all whom it may concern:

Be it known that I, FREEMAN CASS, a citizen of the United States, and residing at Brooklyn, Kings county, State of New York, have invented certain new and useful Improvements in Feed-Rollers for Spinning Mechanism, of which the following is a specification.

This invention relates to thread spinning machines and particularly to various detailed improvements in certain of the feed rollers employed in such machines.

In machines of the kind mentioned it has been found advantageous to use rollers and other thread engaging parts made of porcelain. This material resists the wear or cutting action of the threads to a greater extent than metal and its glazed surface remains smooth, thus minimizing the tendency of the rollers to catch the threads and break the same which results in wastage of material, particularly when the ends of the threads become entangled in the gears and other parts of the machine.

It is the aim of the present invention to provide means for improving the operation of the rollers in machines of the kind referred to, particularly when porcelain rollers are employed. One of these objects is to provide an arrangement by which the threads as they pass about the rollers are held away from the gears which drive the rollers and are prevented from catching between the ends of the rollers and the gears, so that the loss of material and inconvenience occurring by the entanglement of the threads with the gears may be largely avoided. Another object is to provide the surface of the rollers with a groove extending longitudinally thereof for a purpose herein-after pointed out, and a still further object of the invention is to provide a special means for mounting the roller, such means comprising a bushing made of wood which, as will later appear, is of particular value in connection with porcelain rollers.

With these and other objects in view the invention is set forth in the following specification and embraced in the appended claims and the same is illustrated in the accompanying drawings in which:

Figure 1 is a view in elevation illustrating the general arrangement of a part of a machine to which the present invention is applied;

Fig. 2 is a plan view illustrating the posi-

tion and arrangement of the rollers employed in such machines and also showing the manner in which the threads are carried about such rollers;

Fig. 3 is a longitudinal sectional view through one of the rollers involving the present invention;

Fig. 4 is a perspective view of one of the improved rollers of the present invention;

Fig. 5 is a transverse sectional view along the line 5—5 of Fig. 3.

Referring to the drawings in detail the numeral 10 represents a series of spools which carry the supply of threads to be used in the machine. These threads after passing a guide member 11 are carried around the feed rollers and after passing such rollers are led into the other parts of the machine which have no relation to the present invention and which it is unnecessary to illustrate or describe. The rollers made according to the present invention are mounted in a suitable frame 12, there being two of such rollers carried in each frame. The rollers are mounted on spindles 13 which are arranged in suitable bearings 14 formed in the frame, and a gear wheel 14^a, driven in any suitable manner, co-operates with gears secured to the rollers in a manner later described.

The two rollers are identical in construction and a description of one of them will be sufficient. Referring particularly to Figs. 3 and 4 of the drawings it will be noted that the roller proper designated by the numeral 15, is of tubular form and it is to be understood that such roller is made from porcelain having the outer surface thereof glazed which, as heretofore pointed out, effectively resists wear by the threads, and since such glazed surface is smooth and free from projections the threads are not liable to catch upon such surface and be broken. One feature of the present invention consists in providing a groove 16 which extends longitudinally of the roller. This becomes of value in case the threads are broken and wound about the roller. When this happens a knife blade or other suitable cutting tool can be inserted in this groove and by drawing or pushing the same longitudinally of the roller the threads wound about the roller can be cut and removed therefrom.

Contact of the cutting tool with the operating surface of the roller is therefore avoided and this is particularly desirable since such cutting tool is apt to break or mar the

surface of the roller resulting in the formation of minute projections or a roughened portion which would tend to catch and break the threads.

5 On its inner surface the tubular roller 15 is provided with a rib 17 and a bushing 18 preferably made of wood is inserted in the bore of the roller, such bushing being provided with a suitable groove 18^a for engaging 10 the rib formed on the inner surface of the roller 15. The bushing 18 is suitably mounted upon the spindle 13 to which reference has already been made.

The bushing 18 is so arranged as to extend 15 some distance beyond the end of the roller 15 and on such projecting end of the bushing a socket member 19 is mounted this socket member 19 being secured to the bushing in any suitable manner, as by frictional engagement of the parts so that as 20 said member is caused to rotate the bushing and the roller will rotate therewith. A gear wheel 20 is non-rotatably mounted upon the socket member 19, this gear wheel constituting 25 means by which the roller is rotated. As heretofore noted, each of the rollers mounted in the frame 12 are so arranged that their gear wheels 20 will contact with and receive motion from a common driving 30 gear 14.

It will be observed that the socket member 19 is made up of three portions, the bearing or gear supporting portion 19^a, which is mounted on the bushing 18, the 35 web portion 19^b which extends outwardly at right angles to the portion 19^a and the outer annular portion 19^c, part of which is adapted to surround and closely fit the outer surface of the roller inserted in the 40 socket. The outer edge or periphery of the annular portion 19^c adjacent the gear wheel 20 is substantially flush with the outer ends of the teeth of this wheel and the outer surface of said portion 19^c is inclined from 45 a point adjacent the gear wheel inwardly toward the opposite side or, in other words, said surface is inclined outwardly with reference to the outer surface of the roller mounted within this member. The provision 50 of such inclined surface arranged around the end of the roller adjacent the gear wheel constitutes an important feature of the present invention since it tends to keep the threads away from the gear wheel, thus preventing entanglement of the threads 55 in the gear teeth or catching of the same between the end of the roller and the gear wheel.

The foregoing construction constitutes 60 simple and effective means for securing together the roller and gear wheel and for providing the inclined surface surrounding the roller adjacent the gear wheel. It is obvious, however, that a collar or similar 65 portion corresponding to the annular por-

tion 19^c of the member 19 may be secured in position in other ways and that various other changes in construction may be resorted to without departing from the spirit of the invention.

As heretofore noted, the bushing 18 is made of wood, the purpose of which, as has already been indicated, is to enable such bushing to be securely fastened to the porcelain roller 15. In the manufacture of articles of porcelain the parts are apt to become more or less distorted or roughened and in order that a roller made of porcelain such as that heretofore described may be tightly secured to a bushing, it is necessary 70 that the bushing be made of material which will yield more or less and accommodate itself to any unevenness or irregularity in the bore of the roller. Obviously, a metal bushing will not answer this purpose. On the other hand, it has been found that porcelain rollers of the kind described can be securely and satisfactorily mounted on bushings made of wood by forcing the rollers upon the bushings.

Having thus described the invention what is claimed as new and desired to be secured by Letters Patent is:

1. In a mechanism of the kind described, a roller, a gear wheel arranged adjacent one end of the same and operatively connected thereto, means on said roller adjacent said gear wheel for preventing engagement of the threads with said gear wheel, the outer surface of said means being inclined outwardly with reference to the outer surface of the roller and toward said gear wheel.

2. In a mechanism of the kind described, a roller, a member in which one end of the roller is mounted, said member surrounding and closely fitting the aforementioned end of the roller, the outer surface of said member being inclined outwardly from the outer surface of the roller, and means for rotating said roller.

3. In a mechanism of the kind described, a roller, a member in which one end of said roller is mounted, the portion of said member surrounding said roller having a surface inclined outwardly with reference to the outer surface of the roller, and a gear wheel operatively connected with said roller for rotating the same.

4. In a mechanism of the kind described, a roller, a gear wheel arranged adjacent one end of the roller for rotating the same, a member in which the aforementioned end of the roller is mounted, said member being also arranged adjacent said gear wheel and surrounding and closely fitting the end of the roller, the portion of said member surrounding the roller having an outer surface inclined outwardly from the surface of the roller toward the gear wheel.

5. In a mechanism of the kind described,

5 a roller, a gear wheel operatively connected to said roller and arranged adjacent one end thereof, a member arranged adjacent said gear wheel and extending outwardly substantially flush with the outer ends of the teeth of said wheel, the end of said roller adjacent said gear wheel being arranged in said member, the latter surrounding and closely fitting the outer surface of the roller 10 and having its outer surface inclined outwardly from the outer surface of the roller toward the teeth of the gear wheel.

15 6. In a mechanism of the kind described, a roller, a gear wheel arranged adjacent one end of said roller for rotating the same, a socket member also arranged adjacent said gear wheel, the end of said roller adjacent the gear wheel being mounted in said socket member, the latter surrounding and closely 20 fitting said end of the roller and having its outer surface inclined outwardly from the outer surface of the roller and toward said gear wheel.

25 7. In a mechanism of the kind described, a roller, a socket member in which one end of said roller is mounted, said socket member comprising a web portion extending transversely of the end of the roller and an annular portion surrounding and closely fitting a portion of said roller, said annular portion having its outer surface inclined outwardly from the outer surface of the roller toward the web portion of the said member, and means for rotating said roller.

30 35 8. In a mechanism of the kind described,

a socket member having a gear supporting portion and a web portion extending outwardly from said gear supporting portion, a gear wheel mounted on said gear supporting portion and extending outwardly adjacent said web portion, a roller having one end mounted in a socket of said member, said member having an annular portion surrounding and closely fitting a part of the outer surface of said roller, the outer surface of said annular portion being inclined from the outer surface of said roller toward said gear wheel.

40 9. In a mechanism of the kind described, a tubular roller, a bushing composed of wood non-rotatably mounted therein, a gear wheel secured to said bushing, a member surrounding said bushing and arranged adjacent said gear wheel, one end of said roller being arranged in said member and the latter surrounding and closely fitting said roller, the outer surface of said member being inclined from the outer surface of the roller toward the gear wheel.

45 50 55 10. In a mechanism of the kind described, a tubular roller composed of porcelain and having a rib formed on its inner surface, a bushing composed of wood on which said roller is mounted, said bushing being adapted to tightly fit within said roller, said bushing being provided with a groove engaging said rib, and a gear wheel mounted on said bushing for rotating said bushing and roller.

60 65 In testimony whereof I affix my signature.

FREEMAN CASS.
